[57] CLAIM

The ornamental design for a tether toy, as shown and described.

DESCRIPTION

FIG. 1 is a side elevational view of a tether toy showing my new design;

FIG. 2 is a top plan view thereof;

FIG. 3 is a bottom plan view thereof;

FIG. 4 is a side elevational view thereof, with the members shown separated;

FIG. 5 is a cross sectional view of the top member taken along line 5—5 in FIG. 4;

FIG. 6 is a cross-sectional view of a modified embodiment of the top member of the design as shown in FIGS. 1 and 2 taken along line 5—5 of FIG. 4.

The unshown sides of the claimed design opposite FIGS. 1 and 4 are substantially identical. Portions of the tether member have been shown in fragment in FIGS. 1, and 4 to indicate indeterminate length.
